FLUTED CONVEXO-ASPHERIC LENS

Howard A. Schaefer, Lancaster, Ohio, assignor to
Anchor Hocking Corporation, Lancaster, Ohio

Filed Apr. 2, 1970, Ser. No. 22,208

Term of patent 14 years

Int. Cl. D26—06, 99

U.S. Cl. D48—32

Fig. 6.

Fig. 5.

Fig. 8.

Fig. 7.

Fig. 10.

Fig. 9.

Fig. 12.

Fig. 11.

FIG. 1 is a front elevational view of a fluted convexo-aspHERIC lens showing my new design;

FIG. 2 is a side elevational view of the lens shown in FIG. 1 illustrating the aspheric curvature on the frontal surface with the peripheral concave flutes and illustrating the convex rear surface which is in the form of a spherical segment;

FIG. 3 is a rear elevational view of the lens shown in FIGS. 1-2;

FIG. 4 is a cross-sectional view taken through FIG. 1 along the line 4-4 illustrating each of the peripheral flutes to have a spherical segmental cross-section;

FIG. 5 is a front elevational view of a fluted convexo-aspHERIC lens showing a modified form of my design;

FIG. 6 is a side elevational view of the lens shown in FIG. 9 illustrating the aspheric curvature on the frontal surface with the peripheral concavo-convex flutes and illustrating the convex rear surface which is in the form of a spherical segment;

FIG. 7 is a rear elevational view of the lens shown in FIGS. 5-6;

FIG. 8 is a cross-sectional view taken through FIG. 5 along the line 8-8 illustrating each of the peripheral flutes to have a spherical segmental cross-section;

FIG. 9 is a front elevational view of a fluted convexo-aspHERIC lens showing a further modified form of my design;

FIG. 10 is a side elevational view of the lens shown in FIG. 9 illustrating the aspheric curvature on the frontal surface with the peripheral convex flutes and illustrating the convex rear surface which is in the form of a spherical segment;

FIG. 11 is a rear elevational view of the lens shown in FIGS. 9-10; and

FIG. 12 is a cross-sectional view taken through FIG. 9 along the line 12-12 illustrating each of the peripheral flutes to have a spherical segmental cross-section.

I claim:

The ornamental design for a fluted convexo-aspHERIC lens, substantially as shown and described.
